L. CRUVEILHER

GOBLET

Filed Aug. 26, 1925

INVENTOR
Louis Cruveilher,

BY *Mock + Blum*

ATTORNEYS.

UNITED STATES PATENT OFFICE.

LOUIS CRUVEILHER, OF NEW YORK, N. Y., ASSIGNOR TO SOCIETE ANONYME DES CRISTALLERIES DU VAL ST. LAMBERT, OF VAL ST. LAMBERT, BELGIUM.

DESIGN FOR A GOBLET.

Application filed August 26, 1925. Serial No. 14,603. Term of patent 14 years.

To all whom it may concern:

Be it known that I, LOUIS CRUVEILHER, a citizen of the United States of America, residing at New York, in the county of New York and State of New York, have invented a new, original, and ornamental Design for Goblet, of which the following is a specification, reference being had to

the accompanying drawing, forming a part thereof.

The drawing shows a perspective view of a goblet showing my new design.

I claim:

The ornamental design for a goblet as shown.

LOUIS CRUVEILHER.
